CLAIM

The ornamental design for a motorcycle fork light housing, as shown and described.

DESCRIPTION

FIG. 1 is a perspective view of the fork light housing.

FIG. 2 is a front elevation view thereof.

FIG. 3 is a rear elevation view thereof.

FIG. 4 is a top side view thereof.

FIG. 5 is a bottom side view thereof.

FIG. 6 is a first side view thereof; and,

FIG. 7 is a second side view thereof, opposite the first side view.

The features within the housing and the rear surface shown in broken lines form no part of the claimed design.
